AUXILIARY AIR INTAKE FOR MOTORS

Filed Dec. 21, 1925

UNITED STATES PATENT OFFICE.

PERCY W. STEPHENS, OF CHICAGO, ILLINOIS.

AUXILIARY AIR INTAKE FOR MOTORS.

Application filed December 21, 1925. Serial No. 76,790.

This invention relates to improvements in auxiliary air intake devices for internal combustion engines, and has for its principal object to produce a device of the character described, capable of permitting an auxiliary supply of air to be drawn into the intake manifold when the motor is heated, and has for a further object to provide an improved construction whereby the device 5 may be readily attached in ordinary manifold couplings without requiring extra drilling or machining of the standard parts of a motor.

The invention may be best understood by 15 reference to the accompanying drawings which illustrate certain preferred forms thereof.

In the drawings—

Figure 1 is a fragmentary view of a motor showing an intake manifold and carburetor having my improved device attached thereto.

Figure 2 is a detailed section taken on lines 2—2 of Figure 1.

Figure 3 is a detailed section taken on lines 3—3 of Figure 2.

Figure 4 is a detailed section taken on lines 4—4 of Figure 1.

Figure 5 is a detailed section taken on lines 5—5 of Figure 1.

Figure 6 is a view of a modified form of my device, and

Figure 7 is a view of another form of my device.

Referring first to the embodiment of my invention illustrated in Figures 1 to 5 inclusive, the same is shown as applied to an internal combustion motor of which the inlet port 10 opening is shown herein, together with the intake manifold consisting of a horizontally disposed pipe 11 having the usual branches leading to the several motor cylinders, and a vertically disposed connecting pipe 12 having flange 13 of the usual form to which may be attached a carburetor of any suitable form indicated at 14.

In the form shown the motor also has an exhaust duct 15 cast integral with the intake manifold and arranged so that the heat 50 from the exhaust gases tend to preheat the incoming charges passing through the adjacent intake manifold 11.

Referring more specifically to my improved attachment, I provide a thermostatic control device 19 comprising a casing 21 having a valve member 22 connected with a thermostatic element 20 for controlling an inlet port 24 at the lower end of the casing 21. In the form shown in Figures 1, 2 and 3, the casing 21 comprises a cylindrical member having a threaded plug 25 at its lower end through which the inlet opening 24 is formed and a cap 25 threaded in the upper end thereof, said cap also forming a securing device for the thermostat element 20, 60 herein shown as a C-shaped bi-metallic member having the usual thermostatic properties whereby the valve member 22 will normally maintain the inlet opening 24 closed when under ordinary temperature, 70 but when the thermostatic member is heated, as by the heat from the motor, the air inlet will be opened.

In the form shown in Figure 3 I also provide a check valve in the casing 21, comprising a ball 28 which is normally maintained by gravity so as to close the air inlet port 24.

The entire valve and thermostatic mechanism above described is supported on a tube 80 30, arranged so as to communicate at one end with the intake manifold, but preferably capable of being bent so as to support the thermostatic device and inlet valve in a position adjacent a part of the motor which is normally heated during the operation of the motor. As herein shown the pipe 30 is arranged so as to support the thermostatic device beneath and adjacent the exhaust pipe 15 and close to the side of the intake manifold, but it is manifest that the position of the tube may be varied widely to accommodate the device to various types and constructions of motors.

In order to insure the positive operation 95 of the thermostat by the heat radiating from the adjacent motor parts, I provide a shield 31, suitably connected to the pipe 30 as by a clip 32, and arranged in front of the thermostat so as to shield the same from 100 air currents such as are usually present for cooling motors of the type described.

The use and operation of the device above described will now be manifest. An auxil-

iary supply of air will be drawn into the intake manifold after the motor has become heated, thus affording a richer mixture when starting the motor than after the motor has become heated and a thinner mixture is desirable. The quantity of air admitted of course varies with the heat of the motor, which causes the thermostat valve 22 to open to a greater or less degree in proportion to the motor temperature. The check valve opens automatically to admit the air when the suction admitted through the part 24 is sufficient to raise the ball 28.

Referring now to the means for attaching the pipe 30 to the manifold, I provide a special form of bolt 35, of standard length and thread so as to be substituted for one of the standard bolts used in connecting the carburetor 14 to the manifold flange 13.

Details of the bolt 35 are shown in Figures 4 and 5, in which it will be observed that the pipe 30 is arranged to be tapped in the head 36 of said bolt with a duct 37 drilled co-axially for a portion of the length of the bolt and communicating with two laterally extending passageways 38—38 communicating with a grooved portion 39 about the body 40 of said bolt, adjacent the middle thereof. The extreme end of the body of the bolt is threaded at 41 in the usual manner. In connection with the bolt 35 above described, I provide a special form of gasket 42, adapted to fit the manifold flange 13 in the usual manner, but with one side of said gasket having a slotted portion 43 arranged to extend into registering position with one of the bolt holes, and thus receive the bolt 35 through the outer end thereof, when the latter is inserted in securing position, as is clearly shown in Figures 4 and 5. The thickness of the gasket is such as to provide a communication for air entering the tube 30 and passing through ducts 37 and holes 38—38 into the slotted extension 43 and thus into the interior of the manifold pipe 12. The groove 39 is preferably formed of substantial width, being somewhat wider than the gasket 42 so that communication between holes 38, 38 and the gasket slot 43 will be afforded for varying thicknesses of manifold and carburetor flanges with which the bolt may be utilized.

It will be observed from the above description that my improved form of bolt and gasket may be utilized in connection with standard forms of manifold and provide the desired air intake without equipping any additional machinery or tapping of the manifold or carburetor bodies.

Referring to the modified form of device shown in Figure 6, the same form of thermostat element 20 and valve 22 is shown, but in which the valve 22 is seated on the end of the pipe 45 and communicates with a check valve 46, intermediate the thermostat ele-

ment and the manifold. The check valve in this instance comprises a ball 47 maintained under tension in a spring 48 to close the lower end of the pipe 45, this form being especially desirable to insure that the check valve will be positively closed, regardless of the position and arrangement of the casing 46, and also that a greater pressure may be provided, if desired, to maintain the check valve closed until the suction tending to open said valve has reached a predetermined value. On the modified form shown the casing 46 is connected by another pipe 49 to a tap 50 which may be formed directly in a manifold coupling 51, or, if desired, may be tapped into the usual manifold itself. A shield 31^a similar in function to the shield 31 described in connection with Figures 1 and 2, is also provided, but in this form said shield together with the thermostat element 20 are positively secured to the tube 45 by means of a pair of nuts 52—52 threaded on the tube 45 as shown. By means of this arrangement the shield 31^a and thermostat elements 20 may be rotated independently of each other, making it possible for them to be readily readjusted to any desired angular position relative to the tube and the motor to which the device is applied, for the purpose of fitting them snugly in the most convenient co-operating position adjacent the side of said motor.

In the form shown in Figure 7 the same form of bolt 35 is shown as attached to the flange of the carburetor and manifold, but in which the pipe 30^a leads to a simple check valve including a casing 21^a and a ball 28^a maintained by gravity to close an inlet port 24^a.

I claim as my invention:

1. A device of the character described, comprising a tube having means at one end for attachment to a manifold, a valve at the other end of said tube, a thermostat device on said tube for controlling said valve, a shield for said thermostat device carried on said tube said tube being readily bent to adjustably support said thermostat and shield in co-operating position relative to the motor whereby it is responsive to the heat of said motor to open said valve.

2. A device of the character described, comprising a tube having means at one end for attachment to a manifold, a valve at the other end of said tube, a curved thermostat element fixed at one end on said tube and having the other end adapted to control said valve, said tube being arranged to support said thermostat in co-operating position relative to the motor whereby it is responsive to the heat of said motor to open said valve, and a check-valve intermediate the ends of said tube affording passage of air therethrough only under a predetermined amount of suction in said manifold.

3. A device of the character described, comprising a tube having means at one end for attachment to a manifold, a valve at the other end of said tube, a thermostat device on said tube for controlling said valve, said tube being arranged to support said thermostat in co-operating position relative to the motor whereby it is responsive to the heat of said motor to open said valve, and a shield adjustably mounted on said tube relative to said thermostat device.

Signed at Chicago, Ill., this 1st day of December 1925.

PERCY W. STEPHENS.
